UNITED STATES PATENT OFFICE.

HARRISON J. MITCHELL, OF BELOIT, WISCONSIN, ASSIGNOR TO THE BERLIN MACHINE WORKS, OF BELOIT, WISCONSIN, A CORPORATION OF WISCONSIN.

SANDPAPER-DRUM.

1,016,511.

Specification of Letters Patent.

Patented Feb. 6, 1912.

Application filed July 5, 1910. Serial No. 570,364.

To all whom it may concern:

Be it known that I, HARRISON J. MITCHELL, a citizen of the United States, residing at Beloit, in the county of Rock and State 5 of Wisconsin, have invented certain new and useful Improvements in Sandpaper-Drums, of which the following is a specification.

My invention relates to sandpaper drums, 10 and has special reference to the mechanism for attaching and stretching the sandpaper or other abrasive material on the surface of the drum.

In my invention I employ a drum in the 15 periphery of which there is a longitudinal groove. Placed within the periphery or shell of the drum, and on either side of the longitudinal groove, are a pair of abutment shafts against which the opposite edges of 20 the abrasive material are brought. Beneath the abrasive material is preferably placed a layer of felt or the like, one edge of which is attached to one of the abutment shafts, and the other edge of which is secured in 25 position by means of a spring clamp which is held by a rod provided with a plurality of cam portions. Passing longitudinally through the shell, between the shaft on which the drum is mounted and the periphery of the same, is a clamping shaft preferably hollow and provided with a slot in its 30 periphery and on which is mounted a plurality of spring clips, each clip consisting of a pair of leaf spring members which are normally separated from each other. These 35 spring leaf members engage the abutment shafts above mentioned, and serve to hold the edges of the sandpaper or other abrasive material in proper position. This clamping 40 shaft, on which the spring clips are mounted, is rotatable by means of a suitable crank which operates on a lever rigidly mounted on the shaft. On rotation of this clamping shaft, one member of each spring clip is 45 separated from the edge of the abrasive material so that the same may be removed or placed in position at will. One of the abutment shafts, above mentioned, is movable toward its companion abutment shaft 50 by means of a suitable cam mechanism so that the two leaf spring members of each spring clip may be brought together, thereby serving to securely clamp the edges of the abrasive material in position. When 55 this operation has been performed, the mov-

able abutment shaft is rotated through the medium of a torsion spring, and a leaf spring projecting from the movable abutment shaft thereby engages the abrasive material and serves to tighten the same on the drum. 60 These and other advantages of my invention will be more readily understood by reference to the accompanying drawings in which:

Figure 1 is a side elevation and partly 65 vertical longitudinal section on a reduced scale taken on the line 1—1 of Fig. 4. Fig. 2 is a vertical longitudinal section on a reduced scale taken on line 2—2 of Fig. 4. Fig. 3 is an end elevation of the drum and 70 its associated parts, the cap at the end of the drum being removed. Fig. 4 is an end elevation similar to that shown in Fig. 3 except that certain parts have been removed in order to show the underlying parts with 75 greater clearness. Fig. 5 is a horizontal, longitudinal section on a reduced scale taken on line 5—5 of Fig. 3. Fig. 6 is a fragmentary view of the clamping mechanism shown in Fig. 4, but with certain of 80 the parts shown in another position. Fig. 7 is a fragmentary vertical longitudinal section on the line 7—7 of Fig. 3. Fig. 8 is a fragmentary view of the clamping mechanism shown in Figs. 4 and 6 but with certain of 85 the parts in a different position. Fig. 9 is a perspective view of the felt clamping device. Fig. 10 is a perspective view showing the method of securing the edge of the felt to the metallic strip which 90 fits within one of the abutment shafts. Fig. 11 is an enlarged transverse section on the line 11—11 of Fig. 5. Fig. 12 is a perspective view showing the resilient spring mechanism for rotating the tightening shaft. 95 Fig. 13 is a perspective view of one of the rotatable key members which engage the ends of the spring within the tightening shaft. Fig. 14 is a perspective view of the crank shaft which operates the clamping 100 shaft. Fig. 15 is a perspective view of the slotted lever engaged by the crank shaft shown in Fig. 14. Fig. 16 is a vertical longitudinal section through part of the tightening shaft showing the torsion spring and 105 its engaging key members in position. Fig. 17 is a vertical section on the line 17—17 of Fig. 16.

The drum 25 consists of a plurality of sections 26, each of which has a web 27 and a 110

hub 28 through which the main shaft 29 passes. In the periphery of the drum 25 is a longitudinal slot 30. On one end of the drum 25 is provided a cap 31 having a hub 32 which is mounted on the main shaft 29. The other end of the drum is similarly provided with the cap 33 which is mounted by means of its hub 34 on the same shaft. These caps are held in position by the cap screws 31^a shown in section in Figs. 3 and 4. Passing through the webs 27 of the sections 26, is the hollow abutment shaft 34 having the longitudinal slot 35. This abutment shaft, as clearly shown in Fig. 4, is located 15 just inside of one of the edges of the longitudinal slot 30. As most clearly shown in Fig. 10, the edge of a covering 36 of felt or other similar material is secured within the bent metallic strip 37 which is, in turn, held 20 in position within the abutment shaft 34, the felt passing through the slot 35 in this shaft. The covering material 36 incloses the drum, and as clearly shown in Figs. 3, 4 and 11, passes over the opposite edge to that 25 mentioned above of the slot 30.

Mounted near each end of the drum are the brackets 38 which act as retaining means for the cam rod 39. This rod, as best shown in Fig. 7, has the cam projections 40, and 30 passes through suitable openings in the webs 27. The upper edge of the cam rod 39 engages the grooves 41 in the leaf springs 42, which, as best shown in Fig. 2, are mounted between adjacent webs 27. Attached to one 35 edge of each of the leaf springs 42 by means of the screws 43, is the retaining rod 44 which, as best shown in Fig. 9, is provided with pointed projections 45 on its upper surface. The retaining rod 44 is preferably 40 made in a single piece, and passes completely through the drum 25.

It will be noted that when the cam rod 39 is in the position shown in Figs. 4 and 7, the leaf springs 42 are forced toward the periphery of the drum, and the retaining rod 44 is thereby caused to engage the edge of the felt covering 36 with sufficient pressure to hold the felt in position. If it is desired to release the edge of the felt, the caps 31 45 and 33 are removed from the drum, and the cam rod 39 is driven to the right, as indicated in Fig. 2, or to the left, as indicated in Fig. 7, so that the cam projections 40 are disengaged from the webs 27 and the brackets 38, and the cam rod allowed to move toward the center of the drum. The spring pressure acting through the leaf springs 42 is thereby released from the retaining rod 44, and the edge of the felt covering 36 may 50 readily be removed from its engagement with the rod 44.

Passing through suitable openings in the webs 27, is the clamping shaft 45 which is hollow and provided with the longitudinal 65 slot 46. Mounted within this clamping

shaft, are the leaf springs 47, each of which has a pair of projecting clip members 48 and 49 which are normally separated from each other when pressure is not exerted on the same. As best shown in Fig. 1, the leaf springs 47, having the two clip members 48 and 49, are mounted between adjacent webs 27. Rigidly mounted near the end of the clamping shaft 45, by means of the set-screw 50, is the lever 51 having the longitudinal slot 52 and the pin 53 across its end, as best shown in Fig. 15. The short crank shaft 54, having the crank 55, is mounted on the end of shaft 56, which is, in turn, rigidly mounted in the webs 27. The collar 57 prevents inward movement of the sleeved portion 58 of the crank shaft 54 and outward movement of the same is prevented by engagement of the inner surfaces of the two members of the crank 55 with the lever 51. 70 The end of the crank shaft is provided with the slot 59 which may be engaged by a suitable key. Rotatably mounted on the clamping shaft 45, are the wedging members 60, one of which is located in a position adjacent to each of the webs 27. Each of these wedging members is rigidly attached to the sleeve 61 inclosing the tightening shaft 61^a, the former acting also as an abutment shaft, as will be explained hereafter. Each of 75 the wedging members 60, as most clearly shown in Figs. 11 and 12, is also provided with a beveled edge 62, these edges being engaged by the wedge shaped cams 63, mounted on the cam shaft 64. The end of cam 100 shaft 64 is threaded at 65, and has mounted thereon the sleeve 66 provided on its end with the nut 67 which may be engaged by a suitable wrench. Inasmuch as the wedge-shaped cam 63 passes through similarly 105 shaped openings in the webs 27, it will be apparent that on rotation of the sleeve 66, the cam shaft 64 will be moved longitudinally, and thereby correspondingly move the wedging members 60 on the clamping shaft 110 45 as an axis.

As most clearly shown in Figs. 11 and 12 the sleeve 61 is provided with a slot 68 through which project the tightening leaf springs 69 which are mounted within the hollow tightening shaft 61^a. The end of the hollow tightening shaft 61^a has a pair of slots on opposite sides which are engaged by one of the spring retaining key members 70. The shape of this key member is best 115 shown in Fig. 13. The ends of the torsion spring 71 engage the abutment portions 72 of the key members 70 between which this spring is located. A ratchet 73 is loosely mounted on the end of the sleeve 61 and is provided with a slot 74 which engages the projection 75 of the key member 70, located at the end of the sleeve 61. From the outside, the slot 74 of the ratchet 73 may be engaged by any suitable key and turned there- 120 125 130

by. A pawl 76 is mounted on the main shaft 29 and serves to hold the ratchet 73 in the position to which it may be turned.

In order to secure an even rotation of the 5 drum on the main shaft 29, the weights 77 are provided in order to counter-balance the weight of the various adjusting parts which I have described.

Having described the construction of the 10 various parts of my improved sandpaper drum, its operation may now be readily understood. One edge of the felt covering 36 is attached to the retaining strip 37 within the abutment shaft 34. The covering material 15 is then wound around the periphery of the drum and is engaged by the retaining rod 44 in the manner as has already been described. The edge of the sandpaper or other 20 abrading material 78 is next placed against the abutment shaft or sleeve 61 where it is held in position by means of the clip member 49. The sleeve 66 has meanwhile been 25 rotated so that the wedge-shaped cams 63 have allowed the wedging members 60 to move to their maximum position to the right, as shown in Fig. 8. The abrading material is now wound around the drum and its disengaged edge 79, as shown in Fig. 30, is brought into a position opposite to the abutment shaft 34. The crank shaft 54 is now rotated so that the clamping shaft 45 is rotated in a contra-clockwise direction. The clip member 48 is now brought into engagement with the edge 79 of the sandpaper 35 and holds the same against the abutment shaft 34, the clip member 49 meanwhile remaining in engagement with the edge of the abrading material 78 which is in contact with the sleeve 61. The sleeve 66 is now rotated 40 in order to move the cam shaft 64 so that the wedge-shaped cams 63 will force the wedging members 60 to the left, as shown in Figs. 4, 6 and 8, until the two clip members 48 and 49 are brought into contact 45 with each other, and firmly hold the edges of the sandpaper in contact with the abutment shafts 34 and 61. In order to still further tighten the sandpaper, the ratchet 73 is now rotated in a contra-clockwise 50 direction by the engagement of a suitable key with the slot 74 of this ratchet, the effect of such rotation being to rotate the tightening shaft 61 within the sleeve 61 thereby carrying the leaf spring 69 into contact with the sandpaper, as clearly indicated in Fig. 6. It will be noted that this action is effected 55 through the medium of the torsion spring 71 so that the engagement of the leaf spring 69 with the sandpaper is of a resilient nature.

It will be apparent to those skilled in the art that many changes could be made in the detailed construction of the parts which I have described without departing from the 60 spirit of my invention.

What I claim is:

1. In a device of the class described, the combination of a longitudinally-grooved shell, an abutment in said shell, a clamping member in said shell, means for moving said clamping member toward said abutment to clamp the edge of a sheet of abrading material between said parts, and means for retaining the edges of said sheet, during adjustment, in contact with said abutment and said clamping member. 70

2. In a device of the class described, the combination of a shell having a longitudinal groove in its periphery, abrading material wrapped around said shell, means for retaining the edges of the abrading material in said groove, a tightening shaft passing through said shell, a bearing spring attached to and projecting from said shaft, and means for rotating said shaft thereby bringing the bearing spring into contact with the abrading material and tightening the same, substantially as described. 80

3. In a device of the class described, the combination of a shell having a longitudinal groove in its periphery, abrading material wrapped around said shell, means for retaining the edges of the abrading material in said groove, a tightening shaft passing through said shell, a bearing spring attached to and projecting from said shaft, and resilient means for rotating said shaft thereby bringing the bearing spring into contact with the abrading material and tightening the same, substantially as described. 90

4. In a device of the class described, the combination of a cylindrical drum having a longitudinal groove in its periphery, abrading material inclosing said drum, abutment members located inside of the periphery of the drum and adjacent to said longitudinal groove, spring clip members adapted to engage said abutment members and thereby retain the edges of said abrasive 95 material in position, and means for actuating said spring clip members, substantially as described. 100

5. In a device of the class described, the combination of a cylindrical drum having a longitudinal groove in its periphery, abrasive material inclosing said drum, a pair of abutment members adjacent to said groove, a clamping shaft within said drum, spring clip members mounted on said clamping shaft and adapted to engage said abutment members thereby holding opposite edges of the abrading material in contact with said abutment members, and means for rotating said clamping shaft, thereby causing engagement and disengagement of the clip members from said abutment members, substantially as described. 115

6. In a device of the class described, the combination of a cylindrical drum having a 120

- longitudinal groove in its periphery, abutment members adjacent to the edges of said groove, said abutment members adapted to receive the edges of said abrading material, 5 a bearing spring mounted in one of said abutment members, means for actuating said bearing spring, a clamping shaft, clip members mounted in said shaft and engaging said abutment members and thereby retaining 10 in position the edges of said abrading material, means for rotating said clamping shaft thereby causing engagement and disengagement of the clip members with said abutment members, and means for moving 15 one of said abutment members thereby bringing the clip members into contact with each other and firmly clamping the abrading material in position, substantially as described.
- 20 7. In a device of the class described, the combination of a cylindrical drum having a longitudinal groove in its periphery, abutment members adjacent to said groove, abrading material inclosing said drum and 25 passing over said abutment members, means for engaging the edges of said abrading material and holding them in contact with the abutment members, and cam actuated means for moving one of said abutment 30 members, thereby bringing the engaging means into contact with each other and firmly clamping the edges of the abrading material between said engaging means and the abutment members, substantially as de- 35 scribed.
8. In a device of the class described, the combination of a cylindrical drum having a longitudinal groove in its periphery, abutment members adjacent to said groove, 40 abrading material inclosing said drum and passing over said abutment members, means for engaging the edges of said abrading material and holding them in contact with the abutment members, cam actuated means for 45 moving one of said abutment members, thereby bringing the engaging means into contact with each other and firmly clamping the edges of the abrading material between said engaging means and the abutment mem- 50 bers, and a bearing spring associated with one of said abutment members, said bearing spring adapted to engage the abrading material and tighten the same on the drum, substantially as described.
- 55 9. In a device of the class described, the combination of a cylindrical drum having a longitudinal groove in its periphery, abutment members adjacent to the edges of said groove, abrading material inclosing said 60 drum and having its edges passing over said abutment members, a clamping shaft passing through said drum, clip members mounted on said clamping shaft, means for rotating said clamping shaft and thereby bring- 65 ing the clip members into contact with the

abutment members, a wedging member rigidly mounted on said clamping shaft and rigidly connected with one of said abutment members, and cam means for moving said wedging member thereby causing said abutment member to bring the clip members into contact with each other and firmly clamp the edges of the abrading material between said clip members and said abutment members, substantially as described.

70

10. In a device of the class described, the combination of a longitudinally-grooved shell, a pair of members between which the edges of an abrading sheet may be clamped, means for temporarily holding the sheet, during adjustment, and means for causing said members to approach each other and grip said edges.

80

11. In a device of the class described, the combination of a cylindrical drum having a longitudinal groove in its periphery, a resilient covering for said drum, an abutment member adjacent to the longitudinal groove, means for retaining one edge of the resilient covering within said abutment member, a retaining rod adapted to engage the opposite edge of said resilient covering, resilient means for holding said retaining rod in position, and a cam rod for regulating the engaging pressure of said retaining rod on said covering, substantially as described.

85

12. In a device of the class described, the combination of a cylindrical drum having a longitudinal groove in its periphery, abrading material inclosing said drum, means for securing the edges of said abrading material in position within said groove, a tightening shaft passing longitudinally through said drum, a bearing member mounted on said shaft and adapted to engage said abrading material, and resilient means constantly tending to rotate said tightening shaft thereby tightening the abrading material on said drum, substantially as described.

90

13. In a device of the class described, the combination of a cylindrical drum having a longitudinal groove in its periphery, abrading material inclosing said drum, means for securing the edges of said abrading material within said groove, a tightening shaft passing longitudinally through said drum and having a projection adapted to engage said abrading material, a sleeve inclosing said tightening shaft, and resilient means for rotating said tightening shaft independently of said sleeve thereby tightening the abrading material on said drum, substantially as described.

95

14. In a device of the class described, the combination of a longitudinally-grooved shell, a pair of relatively movable members between which the edges of an abrading sheet may be clamped, springs between said members for temporarily holding, during

100

105

110

115

120

125

130

adjustment, the edges of the sheet against said members, and means for forcing said members toward each other.

15. In a device of the class described, the combination of a cylindrical drum, abrading material inclosing said drum, a tightening shaft passing through said drum and having a projection adapted to engage said abrading material, a sleeve inclosing said 5 tightening shaft, a torsion spring in said sleeve, key members on opposite ends of said spring, one of said key members engaging the end of the tightening shaft, and means for rotating the second key member thereby 10 15
- rotating said tightening shaft and causing resilient engagement of its projecting member with the abrading material and tightening the latter on the drum, substantially as described.

- 20 16. In a device of the class described, the

combination of a cylindrical drum, abrading material inclosing said drum, a tightening shaft passing through said drum and having a projection adapted to engage said abrading material, a sleeve inclosing said 25 tightening shaft, a torsion spring in said sleeve, key members on opposite ends of said spring, one of said key members engaging the end of the tightening shaft, and a pawl controlled ratchet engaging said second key 30 member and adapted to rotate the same thereby rotating said tightening shaft and causing resilient engagement of said projecting member with the abrading material and tightening the latter on the drum, substantially as described. 35
